UNITED STATES PATENT OFFICE

2,020,127

ELECTRIC HEATING RESISTOR AND
MOUNTING THEREFORNuman R. Stansel, Schenectady, N. Y., assignor
to General Electric Company, a corporation of
New York

Application November 2, 1932, Serial No. 640,737

3 Claims. (Cl. 13—25)

My invention relates to electric heating resistors, such as used in electric furnaces and other electric heating devices, and has for its object a simple and reliable resistor and mounting therefor for which for a given resistor temperature dissipates heat at a greater aggregate rate than the forms of resistor now in use, whereby lower resistor temperatures can be used for a given heating chamber temperature or conversely higher heating chamber temperatures for a given resistor temperature.

In electric heating devices of the resistor type the resistor operates at a higher temperature than that of the heating chamber, the value of this temperature gradient being determined by the surface area of the resistor. The heat resisting property of the material of the resistor itself is the fundamental factor which limits the maximum operating temperature of the resistor. That is, for each material used as a resistor there is a temperature above which the resistor is either destroyed or rendered unfit for further use. For example, alloys begin to soften and sag at a temperature peculiar to each alloy. With the nickel chromium alloy which is in general use for resistors because of its feature of self-protection against oxidation at elevated temperatures, this protection becomes less and less as the temperature of the resistor increases. Hence in all cases there is an upper limit of operating temperature for the resistor and when using the nickel chromium alloy it is desirable to operate the resistor at as low a temperature as will give the needed rate of heat transfer to the furnace. It is furthermore desirable to operate a resistor at the lowest possible temperature because of the risk of overheating exposed projections and edges of the charge if the temperature of the resistor is considerably in excess of the temperature of the heating chamber. Furthermore, by thus decreasing the temperature gradient between the resistor and the heating chamber, i. e. between the resistor and the gaseous or other medium surrounding the resistor, my invention provides a means of using a higher heating chamber temperature with a resistor of a given material.

In accordance with my invention I increase the surface area of the resistor by means of a plurality of projections or fins which are secured to the resistor along its length in intimate thermal relation with the resistor and in such manner as not to increase the cross sectional area of the current carrying part of the resistor to any appreciable extent. That is, the surface area of the resistor is increased without appreciable decrease

in its electrical resistance and, therefore, without appreciable increase in the rate of heat generation in the resistor for a given applied voltage. This increase in the surface area of the resistor without an increase in its rate of heat generation decreases the rate of heat dissipation per unit surface area of the resistor surface and thus, all other conditions being the same, lowers the operating temperature of the resistor.

The projections may be of the material of the resistor or of another material, as may be best suited in each case. For example, with a non-oxidizing atmosphere in the heating chamber and for temperatures say up to 1600 deg. F. the current carrying portion of the resistor may be a nickel chromium alloy and the projections of copper to take advantage of the comparatively high thermal conductivity of the latter metal. Also the proportion between the added surface area and the original surface area of the resistor can be varied between wide limits as may be best suited in each case.

My invention is not limited to any particular shape of the current carrying portion of the resistor, that is, the current carrying portion of the resistor may be rectangular, round, or any particular shape desired.

For a more complete understanding of my invention, reference should be had to the accompanying drawing in which Fig. 1 is a sectional view of an electric resistor furnace embodying my invention; Fig. 2 is a sectional view of Fig. 1 taken along the line 2—2 looking in the direction of the arrows; Fig. 3 is an enlarged fragmentary sectional view showing details of construction of the resistor shown in Figs. 1 and 2; Fig. 4 is a sectional view taken along the line 4—4 of Fig. 3 looking in the direction of the arrows; Fig. 5 is an enlarged fragmentary sectional view showing a modified construction similar to that of Figs. 3 and 4 but with the current carrying element of the resistor mounted on the inner surface of the wall of the heating chamber; Fig. 6 is a sectional view taken along the line 6—6 of Fig. 5 looking in the direction of the arrows; Figs. 7 and 8 are enlarged fragmentary sectional views similar to Figs. 3 and 4 showing another arrangement of the projections or fins, while Figs. 9 and 10 are similar enlarged fragmentary sectional views showing the application of my invention to the conventional resistor mounted on the inner surfaces of the heating chamber.

Referring to Figs. 1—4, inclusive, of the drawing, I have shown my invention in one form in connection with an electric furnace comprising

a resistor 10 which is in the form of vertical loops, partially embedded in one of the inner walls 11, forming the heating chamber of the furnace. As shown, the resistor is embedded in the side wall, although it may also be applied to the top or bottom walls. The resistor comprises an elongated conductor 12 of uniform cross sectional area throughout its length in which heat is generated. This conductor 12 has a rectangular cross section, as shown in Fig. 4, i. e. it is ribbon-like in shape, although other shapes such as a round wire may be used. As shown, this resistor, formed in vertical loops, is placed in a closely fitting recess, or groove, in the side wall of the furnace so that its outer surface is flush with the inner wall of the furnace. Heretofore, such mountings for the resistance conductor have been prohibitive because of the obstruction offered by the furnace wall to heat dissipation from the faces of the resistor in contact with the wall, by reason of which these embedded surfaces operate at higher temperatures than the inner surface exposed to the interior of the furnace chamber from which heat is readily dissipated. As a result, the furnace temperature is limited to that temperature which can be obtained by operating the embedded portions of the resistor at their maximum permissible temperatures. The portion of the surface of the resistor exposed to the interior of the furnace will thus operate at a lower temperature than the muffled portion. It is obvious, therefore, that if heat were dissipated as freely from the portions in contact with the furnace wall as from the exposed portion, the entire resistor could be operated at its maximum permissible temperature with consequent increase in the temperature of the furnace.

In order to increase the rate of heat dissipation from the embedded portion of the heating resistor, I provide a plurality of projections 13 on this embedded portion, which projections are in direct contact, or otherwise in good thermal relation with the furnace wall. As shown, these projections are rectangular in shape, having a thickness not greater than the thickness of the resistor ribbon 12, so as to provide for a large surface area for heat dissipation for a given volume of metal. These projections are preferably integral with the resistor ribbon, and they are arranged in a series in alignment and spaced apart along the center of the rear surface of the resistor ribbon and extending throughout its length. The resistor may be constructed, for example, by first forming a resistor of continuous T section, short portions of the upright bar of the T being thereafter cut out to form the spaces 14 and thus leave the projections 13. Also the resistor may be constructed by first forming the ribbon 12 as a separate part and thereafter welding or otherwise suitably securing the projections to the ribbon in good thermal relation therewith and at the desired spaced intervals.

It will be observed that the projections, while very greatly increasing the surface area of the embedded portion of the resistor, do not appreciably decrease the total resistance of the resistor for the reason that any current flowing in the shunt path formed by each projection has a longer path than through the ribbon, and consequently a path of greater resistance than through the ribbon itself, for equivalent cross-sectional areas. It will further be observed that the area of the point of junction between each of the heat-radiating projections 13 and the conductor 12 is small as compared with the surface area of that por-

tion of the conductor extending between the ends of each of the members. Consequently, while theoretically there will be some current flow through the projections, it is comparatively small in amount. In other words, by reason of the increased length of the conducting path through the projections the current density in the projections is very low as compared with that in the ribbon. The surface area afforded by the projections may be increased by increasing the height 10 of the projections, that is their dimension in a direction transverse to the resistor and without appreciable decrease in its resistance. As shown the total length of the projections measured lengthwise of the resistor is substantially greater 15 than one-half the length of the resistor. This relation facilitates the conduction of heat from all parts of the heat generating ribbon portion to the projections.

In the operation of the furnace the resistor is 20 connected to a suitable supply source in the conventional manner whereby current is passed through it sufficient to heat it to the desired temperature. The projections 13 by reason of their increase in the surface area of the resistor provide for increased ability in the resistor to 25 dissipate heat by conduction to the furnace wall. In other words, assuming a given amount of heat to be dissipated the increased area afforded by the projections serves to decrease the amount of 30 heat dissipation per unit area of the resistor, the result being that the resistor operates at a lower temperature than would be the case without the projections, assuming the same watts input to the resistor in each case. 35

One object of my invention is to increase the extent of the diffusion within the inner lining by transfer of heat from the resistor to the inner lining by conduction, a feature which is accomplished by mounting the resistor so as to obtain 40 contact of the projections with the material of the inner lining. It will be noted that the formation of an envelope of heat in this manner is not affected by the volume of the charge. Hence less care in the loading of the charge is required and 45 the working capacity of a heating chamber of given dimensions is increased. Obviously the higher the thermometric conductivity (or diffusivity) of the material of the inner lining of the heating chamber the more effective is the above 50 noted feature.

To this end the furnace walls are constructed in two layers, an outer layer or wall 16 of thermal insulating material, such as diatomite, and 55 an inner lining 15 in which the resistor is mounted made of a material having relatively good thermal conductivity as compared with the outer wall, such as silicon carbide or fire brick. The voltage used for the resistor is selected to correspond with the electrical conductivity of the particular material used for the lining so that a relatively small part only of the total current flow is through the lining.

It will be observed that the heat imparted to the lining 15 of the wall is conducted through it 60 to all exposed surfaces of the lining including the top and bottom walls, the lining thereby becoming a secondary source of direct radiation as well as being a source of re-radiation in the usual manner. Therefore, as far as direct radiation is 65 concerned the lining together with the exposed surface of the resistor forms a heat radiating envelope which is not affected by the disposition or size of the charge.

In Figs. 5 and 6 I have shown a form of my 70

invention in which the ribbon part 17 of the resistor is mounted against the inner face of the furnace wall, the projections 18 only being embedded in the furnace wall.

5 In the modified form of my invention shown in Figs. 7 and 8, projections 18 are provided on the surface of the resistor ribbon 20, which is exposed to the interior of the furnace in addition to projections 21 on the embedded portion of 10 the resistor.

10 In Figs. 9 and 10 I have shown my invention as applied to a ribbon resistor 22 which is supported in the furnace in spaced relation to the furnace wall 23, as shown for example in the McFarland 15 Patent No. 1,661,842, dated March 6, 1928. In this case the projections 24 are provided on the inner edge of the ribbon, i. e. on the edge adjacent to the heating chamber, and consequently the projections are free to dissipate heat to the 20 same surrounding medium as the ribbon portion 22.

While I have shown a particular embodiment 25 of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by 30 Letters Patent of the United States is:

1. In an electric furnace, an electric heating resistor comprising a continuous elongated conductor made of resistance heating material, a plurality of heat dissipating projections secured 35 to said conductor and extending laterally therefrom to provide increased heat dissipating area for said conductor without substantially increasing the rate of heat generation of said resistor, and electrically insulating supporting means for

said resistor including a member formed of a material having relatively good thermal conductivity embedding said projections to provide for dissipation of heat therefrom to lower substantially the temperature gradient between said resistor and 5 its surrounding medium.

2. In an electric heating device, outer walls forming a heating chamber made of thermal insulating material, an inner lining for said outer walls formed of a material having a relatively 10 good thermal conductivity as compared with said outer walls, an elongated resistance heating conductor at least partially imbedded in said lining in good thermal relation therewith, heat-dissipating projections on said conductor spaced apart 15 intermediate the ends of said conductor, said projections extending into said inner lining to thereby increase the rate of heat transfer from said resistance conductor to said wall without substantially decreasing the resistance of said conductor, said lining and the exposed portion of said resistor forming a heat-radiating envelope for the 20 charge in said chamber.

3. In an electric heating device, heat refractory walls forming a heating chamber, a lining for at 25 least one of said walls made of a material having relatively good thermal conductivity as compared with said walls, an elongated resistance heating conductor mounted on said lining, and a plurality of heat-dissipating projections spaced at in- 30 tervals on said conductor intermediate its ends in intimate thermal relation therewith and extending into said lining, said projections being arranged to extend laterally into said lining so as to provide increased area for the dissipation of 35 heat from said conductor to said lining without substantially increasing the heat-generating area of said conductor.

NUMAN R. STANSIEL.
